[57] **CLAIM**

The ornamental design for adjustable rack for holding a wok in a barbecue grill, as shown and described.

DESCRIPTION

FIG. 1 is a front elevational view of an adjustable rack for holding a wok in a barbecue grill showing my new design;

FIG. 2 is a top plan view thereof;

FIG. 3 is a left side elevational view thereof, the right side being a mirror image;

FIG. 4 is a rear elevational view thereof;

FIG. 5 is a bottom plan view thereof; and

FIG. 6 is a perspective view thereof, the broken lines indicate the extension of the rack and form no part of the claimed design.

*Fig. 1.**Fig. 3.**Fig. 2.**Fig. 5.**Fig. 4.*

Fig. 6.
